ABSTRACT OF THE DISCLOSURE

A plurality of wires or other elongated flexible elements taken from stationary supply devices are assembled to form a bunch. The bunch is advanced and rotated by a stationary drawing device, which may be a skew roll or an endless belt, having an endless gripping surface which moves in a closed path and engages the bunch over a part of that closed path which is obliquely inclined with respect to the axis of the bunch. The rotating bunch is taken up by a double-twist bunching machine whose flyer rotates in the same direction as the bunch but at a lower speed.

This invention relates to a method of and apparatus for twisting together a plurality of elongated flexible elements by means of a double twist bunching machine. With such machines the flexible elongated elements to be twisted together are drawn off from storage devices (which may be a group of bins or stationary reels or a group of reels of which each reel is mounted for rotation about its axis on a stationary stand) and led into the bunching machine which essentially comprises a take-up device, usually a rotatably driven reel, and a flyer which is rotatably driven about the take-up device and conveys the bunch of elongated flexible elements first forwards axially of the machine and then in a loop rotating around the take-up device (which normally remains stationary in space) and then axially rearwards toward the take-up device. Such machines impart a twist of 720° to the bunched elongated flexible elements during each complete revolution of the flyer of the bunching machine relative to the take-up device, one half of this twist being put in at the entry end of the flyer and the other half at the delivery end of the flyer.

Machines of this kind are relatively cheap as compared with tubular standing or laying-up machines in which the supply reels are mounted in a rotating tube or tubes or in a tubular frame or frames and the twisted together elongated flexible elements are drawn off from a closing die by a capstan or other form of haul-off located at the front end of the tube or frame and thence fed to a take-up reel. Double twist bunching machines are capable of producing technically satisfactory bunched and twisted elongated flexible elements in many cases but difficulties are encountered in attempting to produce on such machines heavy fine wire strand, that is to say strand formed of a very large number of fine wires, for example over two hundred wires. This difficulty arises from the fact that in a given length of strand the length of the individual wires will vary according to the position they occupy in the strand. With tubular strander's and single twist bunching machines there is no difficulty as the wires are automatically drawn off their respective supply devices at correspondingly slightly different rates. In the case of a double twist bunching machine this is possible only with respect to the first twisting stage. Between that stage and

the second twisting stage the wires are locked together and twisting in the second stage can only result in the stretching of the outer wires of the strand or in an excess length of wire in the inner wires of the strand. The former is obviously undesirable; the latter can result in surplus wire being forced outwards from the interior of the strand.

Difficulties are also encountered in attempting to lay-up together on a double twist bunching machine two or more insulated conductors together with fillers in the form of cotton rovings or other elongated elements of low tensile strength used to impart a substantially circular cross-section to the cable before proceeding to apply a tubular braid to, or to extrude a sheath on, the laid-up cores. These are usually manifested by breakage of some of the filler elements.

In copending application Ser. No. 714,479 of Sidney R. Santer, filed Mar. 20, 1968, now U.S. Pat. No. 3,504,487, and assigned to B. & F. Carter & Company Limited, there is described a method of twisting together a plurality of elongated flexible elements which comprises drawing such elements from stationary supply devices, bringing them together and forming them into a twisted bunch by drawing means rotating about a rectilinear axis within the longitudinally advancing bunch and then feeding the rotating bunch thus formed into a double twist bunching machine whose flyer is driven in the same direction as but at a speed less than the speed of rotation of the longitudinally advancing bunch to the extent that at least a substantial proportion of, but not substantially more than, the twist present in the finished product taken up in the bunching machine is put in prior to its entry into the bunching machine, i.e. at a stage where the difference in length of components of the twisted bunch are compensated for by the differing rates of draw-off from their supply devices. If the speed of rotation of the flyer is half that of the bunch at entry into the bunching machine when the take-up is stationary in space, the sole effect of the double twist bunching machine is first to take out half the twist in the rotating bunch being fed into it and then to put back the twist which it has taken out. In the aforesaid specification it is indicated that the drawing means for forming the elongated flexible elements into a twisted bunch is preferably an endless belt type of haul-off which is bodily driven in rotation about an axis coincident with or approximating to the longitudinal axis of advance of the group of elements engaged by it, and/or the axis of the bunching machine associated with it.

The method in accordance with the present invention comprises drawing a plurality of elongated flexible elements from stationary supply devices, assembling them to form a bunch and advancing and twisting the bunch so formed by stationary drawing means having at least one endless gripping surface which moves in a closed path, the said gripping surface engaging the bunch over a part of the closed path which is obliquely inclined with respect to the axis of the bunch and the bunch is fed into a double twist bunching machine whose flyer is driven in the same direction as but at a speed less than the speed of rotation of the longitudinally advancing bunch to the extent that at least a substantial proportion of, but not substantially more than, the twist present in the finished product taken-up in the bunching machine is put in prior to the entry of the bunch into the bunching machine.

By stationary drawings means is meant drawing means having no overall motion which contributes to its advancing and twisting the bunch; minor motion, for example to allow for irregularities in the movement of the bunch, is not excluded.

The endless gripping surface may be the circumferential surface of a driven skew roll, but preferably it is a

surface of a driven endless belt. (By driven, we mean driven other than by engagement with the bunch.) When askew roll is used, it will normally be necessary to use at least one, and preferably more than one, backing roll, which should be skewed at the same angle as the driven roll and may or may not be driven. When an endless belt is used, a backing belt may be used in a similar manner, or alternatively a single belt may be formed into one or more helical turns around and in contact with the bunch. A further possibility is to use a driven roll back by a belt or a driven belt backed by a roll or rolls.

The invention will be more fully described, by way of example, with reference to the accompanying diagrammatic drawings wherein:

FIG. 1 is a general view of apparatus in accordance with the invention,

FIGS. 2 and 3 show one form of drawing means for use in performing the invention; and

FIGS. 4 and 5 show two further forms of drawing means.

As shown in FIG. 1 a plurality of wires or other elements 1 are taken from any convenient source 2 and after passing through appropriately arranged apertures in a guide plate 3 are brought together in a closing die 4. The resulting bunch 5 passes through a drawing device 6 which serves both to draw it forward and to twist it about its own axis. From the drawing device, the twisted bunch passes via a guide 7 to the double-twist bunching machine 8. The twisted bunch 5 now passes around the flyer 9, which may for example be of the kind comprising a lightweight metal bow 10 carrying spaced guides 11 and is taken up on a reel 12 which is held against rotation about the machine axis and is driven about its own axis by gearing of a conventional kind, which has been omitted from the drawing in the interest of clarity. The flyer 9 is driven from a main motor 13 through a layshaft 14 and suitable gears or belts.

The first drawing device to be described is shown in FIGS. 2 and 3, FIG. 3 being a cross-section on the line III-III in FIG. 2, and comprises a skew roll 15 which is driven for example by a motor 16, in a direction to feed the bunch 5 towards the double-twist bunching machine and to twist it with a left-hand lay. Alternatively, a right-hand lay can be obtained by skewing the roll 15 in the opposite direction. Two backing rolls 17 are provided to improve the grip of roll 15 and to avoid applying bending forces to the bunch. Rolls 17 are skewed at the same angle as roll 15, and are preferably also driven, for example by motors 18.

The peripheral surface of the driven roll or rolls should preferably be elastically yieldable so as to ensure contact between it and the bunch over an appreciable area. The skew rolls may be of rubber or rubber-like material or they may be of metal with tyres of such material. The speed of rotation imparted to the bunch and also the linear speed of travel imparted to the bunch will depend upon the peripheral speed of the driven roll or rolls and upon the skew angle, that is to say upon the angle between the axis of the bunch and the axis of the driving roll. The former will vary from a maximum (with the axis of the driving roll parallel to the axis of the bunch) to zero (with the axis of the driving roll at right angles to the axis of the bunch), whilst the linear speed of travel of the bunch will vary from zero to a maximum—assuming that the skew rolls are permitted to govern the linear speed of travel through the double twist bunching machine. By providing for controlled adjustment of the skew of the rolls the pitch of the twist which they impart to the bunch before entry into the machine can be adjusted to any desired value within limits.

FIG. 4 shows a second form of drawing device comprising a single endless driven belt 19 which makes one (or more than one) helical turn around and in contact with the bunch 5. Guide means 20 are provided as close as possible to the point where the belt runs on to the

bunch, and additional guide means 21 as close as possible to its point of departure from the bunch, to control the angle of the helix, and hence the relationship between the rotary speed of the bunch and its linear speed. By 5 making the lead-on and lead-off belt guides adjustable relative to one another in the direction of the length of the bunch and adjustable in an angular direction relative to the axis of the bunch the pitch of the helical turns of the belt about the bunch and hence the pitch of the twist imparted to the bunch may be varied within limits. Each 10 belt guide may comprise a pair of rolls 22, 23, one on each face of the belt, one or both of these rolls having circumferential ribs 24 lying one to each side of the belt, and means for imparting angular and/or linear movement to the roll housing relative to the axis of the bunch upon which the belt operates. One or both of the rolls constituting the belt guide on the departure side of the bunch may be power driven for example by a motor 25 to impart a 15 drive to the belt. Alternatively a separate driving pulley 26 may be used. By providing a jockey pulley 26 or other device to maintain tension in the belt, this drawing device is rendered readily adaptable to bunches of various diameters. The arrangement shown in the drawing requires the use of an endless belt 19 having one twist for each 20 helical turn about the bunch, but this can be avoided by guiding the belt through a second helix having the same 25 number of turns of opposite hand.

A third form of drawing device is shown in FIG. 5 and comprises two endless belts, which for ease of identification will be referred to as the upper belt 27 and the lower belt 28, inclined at the same angle with respect to the axis of the bunch. The lower run of the upper belt and the upper run of the lower belt are slightly spaced from one another, and the bunch 5 passes between and in contact with both of them, the two contact areas being substantially opposite to one another, so that the two belts back each other. Pressure pads 29, 30 engaging respectively the upper face of the lower run of the upper belt 27 and the lower face of the upper run of the lower belt 28 may be used to ensure a high contact area between the belts and the bunch; if required, these may be provided with small rolls or belts to reduce friction. At least one, and preferably each, of the belts 27, 28 is driven so that its bunch-engaging run moves in the direction indicated by the arrow 31 thereon. If both are driven they will of course be driven at the same linear speed. One of many possible drive arrangements is shown and comprises a first bevel gear 32 which is positively driven, preferably through appropriate gearing from the main drive for the double-twist bunching machine, and drives two further bevel gears 33, which are coupled to the rolls 34, 35 supporting the belts 27, 28 by chain-and-sprocket mechanisms 36, 37 respectively.

The arrangement shown in FIG. 5 has the advantage 55 over that shown in FIG. 4 that the bending forces applied to the bunch are much smaller, and it avoids the limitation on the belt width set in the FIG. 4 apparatus set by the onset of interference between adjacent turns of the helix. It is also somewhat easier to adjust the lay angle, e.g. by bodily rotation of each of the belts about the axis of bevel gear 32.

In general, the optimum speed of rotation of the bunched 60 elements fed to the double twist bunching machine by the drawing device is twice that of the flyer of the bunching machine if the bunching machine take-up is stationary in space, as in such a case all the twist present in the finished product taken up in the bunching machine is imparted prior to its entry into the machine i.e. at a point where it is possible to cater for the slight additional length of 65 elements required for the radially outer part of the bunch as compared with the length of elements required for the central part of the bunch. In the present method the bunch is preferably driven in rotation at a speed substantially equal to twice the speed of the flyer of the bunching machine but satisfactory products are obtainable by driv- 70

ing the bunch at speeds somewhat less than twice the speed of the flyer, again assuming the bunching machine take-up is stationary in space. If the speed of the bunch is very substantially less than that of twice the speed of the flyer, the twist imparted to the bunched elements by the skew rolls or endless belt may be insufficient to prevent stretching and possible rupture of the outer elements or a surplus length of elements in the middle of the bunch may occur at the second stage of twisting in the bunching machine. If on the other hand the speed of the bunch substantially exceeds twice the speed of the flyer too much twist may be imparted to the bunched elements by the skew rolls or the endless belt and the twist that will be taken out at the flyer entry may then result in slack outer elements which will not be completely taken up by the twist imparted at the flyer delivery. It will be appreciated that the optimum speed of rotation of the skew rolls or speed of the endless belt and hence the optimum speed of rotation of the bunched elements being fed to the bunching machine can be raised (with an increase in the throughput speed of the product) if the bunching machine take-up is rotated in a direction to add to the twist put in at the delivery end of the flyer e.g. where the take-up device is a reel, by rotating the reel bodily about the machine axis in a direction counter to the direction of rotation of the flyer.

As all the components of the bunch drawing and twisting device will have very much smaller radius of gyration and hence a higher permissible speed of rotation than that of the flyer of the bunching machine, which must be in excess of the radius of the take-up reel, it is possible not only to obtain by our invention a technically satisfactory twisted bunch of elongated flexible elements that cannot be produced on a double twist bunching machine alone, but to obtain it at twice or more than twice the output speed at which it would be obtainable by existing methods on a single twist bunching machine of the same maximum flyer speed of rotation.

What we claim as our invention is:

1. A method of twisting together a plurality of elongated flexible elements, comprising the steps of

(a) assembling the elements as they are withdrawn from stationary supply devices to form a bunch;

(b) advancing and twisting the bunch so formed by stationary drawing means having at least one endless gripping surface which moves in a closed path that is fixed with respect to rotation around the axis of the bunch and engages the bunch over a part of the closed path which is obliquely inclined with respect to the axis of the bunch; and

(c) feeding the bunch into a double-twist bunching machine comprising take-up means and a flyer rotatable around the take-up means, and driving the flyer in the same direction as but at a speed less than the speed of rotation of the longitudinally advancing bunch to the extent that at least a substantial proportion of, but not substantially more than, the twist present in the finished product taken up in the bunching machine is put in prior to the entry of the bunch into the bunching machine.

2. A method as claimed in claim 1 wherein the step of advancing and twisting the bunch is carried out by engaging the bunch with the circumferential surface of at least one driven skew roll which rotates about an axis obliquely inclined with respect to the axis of the bunch and is fixed with respect to rotation around the axis.

3. A method as claimed in claim 2 comprising holding the bunch in engagement with the said driven skew roll by means of at least one backing roll which is rotatable about an axis that is inclined at the same angle as the axis of the driven skew roll with respect to the axis of the bunch and is fixed with respect to rotation around that axis.

4. A method as claimed in claim 3 comprising driving the backing roll.

5. A method as claimed in claim 1 in which the step of advancing and twisting the bunch is carried out by engaging the bunch with at least one driven endless belt having a path that is fixed with respect to rotation around the axis of the bunch over a part of the path of the belt which is obliquely inclined with respect to the axis of the bunch.

10 6. A method as claimed in claim 1 in which the step of advancing and twisting the bunch is carried out by engaging the bunch with a pair of endless belts each having a path that is fixed with respect to rotation around the axis of the bunch and the two belts having respective surfaces which engage the bunch over parts of their respective paths which are equally obliquely inclined with respect to the axis of the bunch and over parts of the bunch which are substantially opposite to one another, so that each of the belts backs the other, and driving both belts at substantially the same longitudinal speed.

15 7. A method as claimed in claim 1 in which the step of advancing and twisting the bunch is carried out by engaging the bunch with an endless belt which makes at least one helical turn around and in contact with the bunch and is driven in a path that is fixed with respect to rotation around the axis of the bunch.

20 8. A method as claimed in claim 1, comprising maintaining the take-up of the bunching machine stationary and rotating the flyer at a speed substantially equal to one-half of the angular speed imparted to the bunch by the drawing device.

25 9. Apparatus for twisting together a plurality of elongated flexible elements withdrawn from stationary supply devices, comprising

(a) means for assembling the elements to form a bunch;

(b) for advancing and twisting the bunch so formed, stationary drawing means having at least one endless gripping surface which moves in a closed path that is fixed with respect to rotation around the axis of the bunch and means for guiding the bunch in engagement with the said gripping surface over a part of its closed path which is obliquely inclined with respect to the axis of the bunch;

(c) a double-twist bunching machine comprising take-up means and a flyer rotatable about the take-up means for receiving the twisted bunch, and

(d) means for driving the flyer of the bunching machine in the same direction as but at a speed less than the speed of rotation of the longitudinally advancing bunch to the extent that at least substantial proportion of, but not substantially more than, the twist present in the finished product taken up in the bunching machine is put in prior to the entry of the bunch into the bunching machine.

10 10. Apparatus as claimed in claim 9 in which the said stationary driving means comprises at least one skew roll mounted for rotation about an axis that is fixed with respect to rotation around the axis of the bunch and means for rotating the skew roll.

11 11. Apparatus as claimed in claim 10 in which the peripheral surface of the or each driven roll is elastically yieldable.

12. Apparatus as claimed in claim 10, comprising at least one backing roll which is skewed at the same angle as the said skew roll, the axis of the backing roll being fixed with respect to rotation around the axis of the bunch.

13. Apparatus as claimed in claim 12, comprising means for driving the backing roll.

14. Apparatus as claimed in claim 9 in which the said stationary drawing means comprises at least one endless belt which is driven in a path that is fixed with respect to rotation around the bunch axis and is arranged to engage the bunch over a part of its path which is obliquely inclined with respect to the axis of the bunch.

15. Apparatus as claimed in claim 14 in which the stationary drawing means further comprises a second endless belt and means for driving the second belt at substantially the same longitudinal speed as the first in another path that is fixed with respect to rotation about the axis of the bunch, the two belts being arranged to be equally obliquely inclined with respect to the axis of the bunch and to engage the bunch over parts thereof which are substantially opposite to one another, so that each of the belts backs the other.

16. Apparatus as claimed in claim 9 in which the said stationary drawing means comprises at least one endless belt, guides which are fixed with respect to rotation about the axis of the bunch for forming the belt into a helix of at least one turn around and in contact with the bunch, and means for driving the endless belt.

17. Apparatus as claimed in claim 9 comprising means so interconnecting the drawing means and the bunching machine that the speed of the flyer of the bunching machine is substantially equal to one-half of the angular speed imparted to the bunch by the drawing device.
